EDGE ROLLING METHOD AND APPARATUS

John W. Sheperdson, Worcester, Mass., assignor
to Morgan Construction Company, Worcester,
Mass., a corporation of Massachusetts

Application January 22, 1936, Serial No. 60,294

19 Claims. (Cl. 80—31.1)

This invention relates to metal rolling, and more particularly to the rolling of skelp, sheet bar, and similar flat rolled products.

In the rolling of flat strips of material it is customary to use edging rolls to control the width of the strip and to provide the desired shape for the edges. In some cases the edging rolls merely prevent or limit the lateral spreading of the material, and in other cases they may serve to effect a substantial reduction in the width of the strip.

Considerable difficulty has been encountered heretofore in the operation of these edging rolls. Because of the high ratio between the width of the strip and its thickness, the strip will buckle unless the compressive force applied thereto by the edging rolls is comparatively low. In some cases it is not possible to apply sufficient pressure to effect any appreciable reduction without buckling. Attempts have been made to overcome the trouble by providing very deep narrow grooves in the rolls. However, these grooves are very difficult and expensive to machine, and they must be of different widths to correspond with various thicknesses of stock. Furthermore, as the bottoms of the grooves become worn and they are dressed to present a true surface, the effective diameter will be decreased, necessitating an adjustment of the speed of rotation in order to maintain the required peripheral speed. In addition, the grooves must be flared in order to ensure proper entering of the stock, and as a result the central portion of the stock between the rolls, being unsupported, will buckle to one side or the other under the rolling pressure.

It is accordingly one object of the invention to provide an improved method of rolling material having a width greater than its thickness, whereby adequate rolling pressures may be applied to the edges of the material without causing buckling thereof.

It is a further object of the invention to provide an improved method of rolling the edges of material having a width greater than its thickness, which can be practiced successfully without requiring deep and narrow grooves in the edging rolls.

It is a further object of the invention to provide a comparatively simple, inexpensive and reliable apparatus for rolling the edges of material having a width greater than its thickness and preventing transverse buckling thereof.

It is a further object of the invention to provide an improved construction of roll for edging mills, which requires no deep narrow grooves and

which is adapted for use with stock of different thicknesses.

It is a further object of the invention to provide an improved construction of roll, which can be dressed after it becomes worn without varying the effective diameter of the roll.

With these and other objects in view, as will be apparent to those skilled in the art, the invention resides in the combination of parts and the steps of the process set forth in the specification and covered by the claims appended hereto.

Referring to the drawings illustrating one embodiment of the invention and in which like reference numerals indicate like parts,

Fig. 1 is a vertical section through a rolling apparatus, the section being taken on the line 1—1 of Fig. 2;

Fig. 12 is a sectional elevation of a further modification, the section being taken on the line 12—12 of Fig. 13;

Fig. 13 is an enlarged section on the line 13—13 of Fig. 12; and

Fig. 14 is a view showing the buckling of stock by edging rolls of a type heretofore used.

In the embodiment illustrated in Fig. 2 there is provided a pair of horizontal rolls 10 which serve to reduce the thickness of a flat strip of material 11 as it travels in the direction indicated by the arrow. These rolls 10 are mounted in the usual housing 12, and they may be driven by any suitable means. It will be understood that these rolls preferably operate only on the flat sides of the strip 11.

In order to maintain the desired width for the strip and to ensure smooth and properly shaped edges, it is customary to use edging rolls. However, great difficulty has been experienced due to the fact that the strip tends to buckle transversely if any appreciable rolling pressure is applied to its edges. This transverse buckling of

the stock is illustrated in Fig. 14, which shows a pair of edging rolls 13 of a conventional type. As indicated by the dotted lines in this figure, the buckling may take place in either direction, and 5 it prevents any accurate control of the width of the rolled strip. This difficulty is overcome by the present invention.

As one step in my improved method, I bend the strip 11 transversely through a small angle in a pre-10 determined direction, preferably into an arc. This can be accomplished by various means. For example, it will be apparent that the bending could be effected in a reducing pass by means of suitably shaped rolls, but this would have the disadvantage 15 of making these rolls expensive and difficult to machine. In the construction illustrated there is provided a pair of horizontal bending rolls 14 and 15, the upper roll 14 being arranged to contact with the upper surface of the strip 11 at the 20 center, and the lower roll 15 being arranged to contact with the lower surface of the strip near the edges, as shown particularly in Fig. 5. If desired, the central portion of the lower roll 15 may be cut away or recessed to avoid contact with 25 the stock. These rolls 14 and 15 are rotatably supported in suitable brackets 16 mounted on the housing 12 at the delivery side thereof. While in some cases idler rolls may be used for bending, I have shown means for driving the rolls 14 and 30 15. For this purpose an electric motor 18 is connected to the lower roll 15 and the two rolls are connected by gears 19. It will be apparent that the rolls 14 and 15 will bend the stock 11 transversely into an arc with the convex side thereof 35 at the bottom, as shown in Fig. 5, the arc preferably extending across substantially the entire width of the stock. This arc is preferably but not necessarily a circular arc.

Following the above described bending operation, 40 rolling pressure is applied to the edges of the stock from opposite directions, and in order to prevent this pressure from buckling the stock the convex side thereof is supported. Various means for furnishing this support will be apparent to those skilled in the art, but I preferably utilize a pair of spaced rolls which are so shaped that they will not only roll the edges of the stock but will also support the convex side of the stock during the rolling operation. These rolls are 50 preferably so constructed that the worn portions thereof may be dressed easily and cheaply, and without changing the effective diameter.

As shown particularly in Fig. 1, there is provided a pair of spaced vertical rolls 21 between 55 which the stock passes after the bending operation. Each roll 21 is mounted on a vertical spindle 22 provided with an outwardly projecting flange 23 forming a shoulder. An annular member 25 is arranged to contact with the upper surface of the flange 23, and this member is provided with a slightly concaved upper surface 26 which contacts with the convex lower surface of the stock 11 to support the same. The annular member 25 is provided with a frusto-conical opening 60 or socket 27 into which there is fitted a conical member 29 which engages the edges of the stock 11. This member 29 is bored centrally to fit the spindle 22, and the various parts are fastened together by a washer 30 and a nut 31 screw-threaded to the upper end of the spindle. When the parts are assembled, the member 25 forms a flange on the roll.

It will now be apparent that the actual rolling pressure on the edges of the stock will be provided 75 by the conical portions 29 of the rolls, and that

most of the wear will be on these portions. It is a comparatively simple matter to disassemble the rolls and to dress off the conical surfaces of these members 29. After this dressing operation the rolls can be reassembled, and the conical portions 29 will be somewhat lower than they were before. However, the effective diameter of the rolls, where they engage the strip, will remain exactly the same as it was originally, and no change in the roll speed will be required.

In case the strip 11 is to be used for skelp, it may be desirable to form beveled edges thereon. This can readily be accomplished by making the conical angle of the rolls of sufficient size. As indicated particularly in Fig. 4, the conical surfaces of the portions 29, if projected upwardly, will intersect at a point considerably below the center of curvature of the strip. As a result, the edges of the strip will be beveled.

Means is preferably provided to adjust the distance between the centers of the spindles 22. For this purpose the spindles are supported beneath the rolls by anti-friction bearings 33 in separate housings 34 and 35. These housings are slidably supported by a fixed hollow rectangular frame 37 carried by a suitable foundation 38. A yoke 39 surrounds the housings to hold them in correct relative positions laterally against the rolling pressure, and this yoke is provided with a manually rotatable horizontal screw 40 which contacts with the housing 35. A bearing 42 is fastened to the frame 37 to support a manually rotatable horizontal screw 43 provided with collars 44 at each side of the bearing. This screw 43 passes through a nut 45 fastened to the housing 34. It will be apparent that by properly manipulating the screws 40 and 43, the housings 34 and 35 can be moved along the frame 37 to any desired positions, and spaced in a desired manner to accommodate rolls of varying diameters and stock of varying widths.

In order to drive the spindles 22, bevel gears 47 are mounted on their lower ends, and these gears mesh with bevel gears 48. The gears 48 may be driven by any suitable means.

After the strip 11 has passed between the edging rolls 21, it will usually be desirable to pass it through additional flattening rolls.

For this purpose there is shown in Fig. 2 a pair of horizontal flattening rolls 56 mounted in a suitable housing 57. It will be apparent that the rolls 56 could be arranged to receive the stock directly from the edging rolls, and that these rolls 56 would in that case both flatten the stock and reduce its thickness. In some cases however it may be desirable to form a loop 58 in the stock between the edging rolls and the rolls 56 in order to prevent tension in the stock. There is a possibility that under certain circumstances the stock might buckle if it entered such a loop while still bent transversely, and in order to prevent such a possibility I have shown a pair of horizontal rolls 60 located close to the delivery side of the edging rolls. The rolls 60 are mounted in a suitable housing 61, and they are connected by gears 62 and driven by an electric motor 63. These rolls flatten the stock before it enters the loop 58.

In the practice of my invention, it is by no means essential to utilize vertical edging rolls, and in some cases it may be preferable to utilize horizontal rolls. In Fig. 7 I have illustrated a pair of horizontal edging rolls 65 each of which is provided with a series of passes of varying depths to accommodate stock of different widths. It

will be noted that each pass is formed with a concave surface 66 to support the convex side of the stock and with a conical surface 67 to apply rolling pressure to the edge of the stock. These 5 rolls 65 may be supported and driven by any suitable means, and suitable provision may be made for bending the stock transversely before it enters the roll pass.

The operation of the invention will now be apparent from the above disclosure. The strip 11 after leaving the flattening rolls 10 passes between the rolls 14 and 15, which bend it transversely into an arc. Since these bending rolls do not reduce the cross-sectional area of the stock, 10 they will require very little power and they will be subjected to very little wear. The transversely bent stock now passes between the edging rolls 21 which apply rolling pressure to the edge of the stock. This pressure of course tends to bend 15 the stock still further, but such further bending is prevented by engagement of the concave surfaces 26 of the rolls with the convex surface of the stock. Consequently it is possible to produce a considerable reduction in the width of the stock 20 without danger of buckling the same. Furthermore, beveled edges may be formed on the stock if desired. After leaving the edging rolls the stock is flattened by passing between the rolls 60 and then enters between the rolls 56 for further 25 reduction in thickness. If the edging rolls are arranged horizontally, as shown in Fig. 7, the operation will be the same, except that the stock will be delivered to these rolls with one edge at the top and the other at the bottom. By using 30 edging rolls of the type shown in Fig. 1, it is possible to dress the rolls very easily and cheaply, and without changing the effective diameter. If the rolls are made solid, as shown in Fig. 7, dressing will affect the diameter. However, the passes 35 in these rolls are comparatively open and much more accessible for dressing than in prior edging rolls. It will be noted that either of the illustrated types of edging roll will accommodate varying thicknesses of stock without change.

40 In Figs. 8, 9 and 10 I have shown a modified form of apparatus. In this embodiment the stock is bent transversely by a suitable shaped guide prior to the edge rolling operation, and after leaving the edging rolls it passes through a further guide which flattens the stock. At the delivery side of the horizontal rolls 10 there is provided a guide box 70 in which are mounted a lower guide plate 71 and an upper guide plate 72. These plates 71 and 72 are held in place by a 45 wedge 73 which is inserted between the top of the upper plate 72 and a transverse bar 74 thereabove, this bar being supported by the sides of the guide box 70. As shown particularly in Fig. 9, the upper guide plate 72 is shaped to force the central portion of the stock downwardly, and the lower guide plate 71 is shaped to force the marginal portions of the stock upwardly, thus producing the desired transverse bending of the stock before it passes between the edging rolls 21. At 50 the delivery side of the edging rolls there is provided a guide box 76 in which are mounted a lower guide plate 77 and an upper guide plate 78. These plates 77 and 78 are held in place by a wedge 80 which is inserted between the top of the upper guide plate 78 and a transverse bar 81 thereabove, this bar being supported by the sides of the guide box 76. As shown particularly in Fig. 10, the lower guide plate 77 is shaped to force the central portion of the stock upwardly, and the upper guide plate 78 is shaped to force the marginal 55 portions of the stock downwardly, thus flattening the stock transversely before it enters the loop 58.

55 The operation of the invention will now be apparent from the above disclosure. The strip 11 after leaving the flattening rolls 10 passes between the rolls 14 and 15, which bend it transversely into an arc. Since these bending rolls do not reduce the cross-sectional area of the stock, they will require very little power and they will be subjected to very little wear. The transversely bent stock now passes between the edging rolls 21 which apply rolling pressure to the edge of the stock. This pressure of course tends to bend the stock still further, but such further bending is prevented by engagement of the concave surfaces 26 of the rolls with the convex surface of the stock. Consequently it is possible to produce a considerable reduction in the width of the stock without danger of buckling the same. Furthermore, beveled edges may be formed on the stock if desired. After leaving the edging rolls the stock is flattened by passing between the rolls 60 and then enters between the rolls 56 for further reduction in thickness. If the edging rolls are arranged horizontally, as shown in Fig. 7, the operation will be the same, except that the stock will be delivered to these rolls with one edge at the top and the other at the bottom. By using edging rolls of the type shown in Fig. 1, it is possible to dress the rolls very easily and cheaply, and without changing the effective diameter. If the rolls are made solid, as shown in Fig. 7, dressing will affect the diameter. However, the passes in these rolls are comparatively open and much more accessible for dressing than in prior edging rolls. It will be noted that either of the illustrated types of edging roll will accommodate varying thicknesses of stock without change.

60 In Figs. 8, 9 and 10 I have shown a modified form of apparatus. In this embodiment the stock is bent transversely by a suitable shaped guide prior to the edge rolling operation, and after leaving the edging rolls it passes through a further guide which flattens the stock. At the delivery side of the horizontal rolls 10 there is provided a guide box 70 in which are mounted a lower guide plate 71 and an upper guide plate 72. These plates 71 and 72 are held in place by a wedge 73 which is inserted between the top of the upper plate 72 and a transverse bar 74 thereabove, this bar being supported by the sides of the guide box 70. As shown particularly in Fig. 9, the upper guide plate 72 is shaped to force the central portion of the stock downwardly, and the lower guide plate 71 is shaped to force the marginal portions of the stock upwardly, thus producing the desired transverse bending of the stock before it passes between the edging rolls 21. At the delivery side of the edging rolls there is provided a guide box 76 in which are mounted a lower guide plate 77 and an upper guide plate 78. These plates 77 and 78 are held in place by a wedge 80 which is inserted between the top of the upper guide plate 78 and a transverse bar 81 thereabove, this bar being supported by the sides of the guide box 76. As shown particularly in Fig. 10, the lower guide plate 77 is shaped to force the central portion of the stock upwardly, and the upper guide plate 78 is shaped to force the marginal portions of the stock downwardly, thus flattening the stock transversely before it enters the loop 58.

In Fig. 11 I have illustrated a construction which it may be desirable to utilize in some cases, particularly if the stock is comparatively wide. In this embodiment there is provided a somewhat different means for supporting the convex side of the stock while the edges thereof are being rolled. As shown, a stationary block or anvil 83 may be mounted between the flange portions 25 of the edging rolls 21, this block 83 having an upper concave surface 84 which contacts with the lower surface of the stock. In operation the stock will slide over the surface 84, which will support the stock and prevent it from buckling under the lateral pressure imposed by the edging rolls.

It will now be clear to those skilled in the art that only a very slight degree of transverse bending of the material is required before it is engaged by the edging rolls. If the material is even slightly bent in the proper direction, the pressure applied to the edges thereof will force the material to bend still further until its convex side is brought into contact with the supporting surfaces. In some cases the flanges 25 may serve not only as a means for supporting the convex side of the material but also as a means for effecting the transverse bending thereof. As shown particularly in Figs. 12 and 13, the material may approach the edging rolls 21 while perfectly flat and in such a position with respect to the roll pass that the corners at the front end of the advancing material will engage the concave surfaces 26 in advance of the conical surfaces of the members 29. The concave surfaces 26 will deflect these corners upwardly and thus produce a slight transverse bending of the material. As soon as the edges of the material are gripped between the conical members 29, the material will be bent still more in the same direction by the lateral pressure until further bending is prevented by engagement of the convex surface of the material with the surfaces 26. As shown in Fig. 12, a guide of usual and ordinary construction may be provided between the horizontal rolls 10 and the edging rolls 21. This guide comprises a guide box 86 in which are mounted a lower guide plate 87 and an upper guide plate 88. A transverse bar 90 is supported by the side walls of the box 86 above the upper plate 88, and a tension spring 91 connects the upper plate 88 with a transverse rod 92 carried by the housing 12. It will be understood that the stock passes between the plates 87 and 88, and that these plates simply guide the stock to the edging rolls without changing the shape of the stock. In this embodiment the edging rolls bend the stock transversely in the proper direction and roll its edges while the convex side of the stock is supported by the concave surfaces 26.

Having thus described my invention, what I claim as new and desire to secure by Letters Patent is:

1. The method of rolling material having a width greater than its thickness comprising the steps of bending the material transversely through a small angle in a predetermined direction, supporting the convex side of the material, and applying rolling pressure to the edges of the material from opposite directions while the convex side thereof is supported.

2. The method of rolling material having a width greater than its thickness comprising the steps of moving the material longitudinally, bend-

ing the material transversely through a small angle in a predetermined direction, supporting the convex side of the material, and applying rolling pressure to the edges of the material from opposite directions while the convex side thereof is supported.

3. The method of rolling material having a width greater than its thickness comprising the steps of bending the material transversely through a small angle in a predetermined direction, supporting the convex side of the material while leaving the concave side thereof unsupported, and applying rolling pressure to the edges of the material from opposite directions while the convex side thereof is supported.

4. Rolling apparatus for producing material having a width greater than its thickness comprising means to bend the material transversely through a small angle in a predetermined direction, means to support the convex side of the material, and means to apply rolling pressure to the edges of the material from opposite directions while the convex side thereof is supported.

5. Rolling apparatus for producing material having a width greater than its thickness comprising means to bend the material transversely through a small angle in a predetermined direction, means to support the convex side of the material, and a pair of spaced rolls to apply rolling pressure respectively to the two edges of the material from opposite directions while the convex side thereof is supported.

6. Rolling apparatus for producing material having a width greater than its thickness comprising means to bend the material transversely through a small angle in a predetermined direction, a pair of spaced rolls to apply rolling pressure respectively to the two edges of the material from opposite directions, and means on said rolls to support the convex side of the material.

40 7. Rolling apparatus for producing material having a width greater than its thickness comprising means to bend the material transversely through a small angle in a predetermined direction, and a pair of spaced rolls each having a pass 45 therein which engages one edge and the convex side of the material.

8. Rolling apparatus for producing material having a width greater than its thickness comprising a pair of spaced rolls having surfaces to apply rolling pressure respectively to the two edges of the material from opposite directions and concave surfaces which support one side only of the material while it is being reduced in width.

55 9. Rolling apparatus for use with elongated strips of material having a width greater than its thickness comprising a pair of spaced rolls rotatable about substantially parallel axes and each having a groove therein, one side of each groove having a conical surface to engage one edge of the strip and the other side having a concave surface which intersects the conical surface and supports one side only of the material 60 while it is being reduced in width.

10. Rolling apparatus for producing material having a width greater than its thickness comprising means to bend the material transversely through a small angle in a predetermined direction, means to support the convex side of the material, and a pair of spaced rolls having conical surfaces to apply rolling pressure respectively to the two edges of the material from opposite directions, the conical angle being of sufficient 70

size to result in the formation of beveled edges on the material.

11. Rolling apparatus for producing material having a width greater than its thickness comprising means to bend the material transversely through a small angle in a predetermined direction, a pair of spaced conical rolls to apply rolling pressure respectively to the two edges of the material from opposite directions, and an annular flange surrounding each roll and separable therefrom, each flange having a concave surface for contact with the convex side of the material. 5

12. Rolling apparatus for producing material having a width greater than its thickness comprising means to bend the material transversely through a small angle in a predetermined direction, a pair of spaced rolls to apply rolling pressure respectively to the two edges of the material from opposite directions, and a stationary block having a concave surface arranged 10 to contact with the convex surface of the material while the edges thereof are being rolled. 15

13. Rolling apparatus for producing material having a width greater than its thickness comprising means to bend the material transversely through a small angle in a predetermined direction, means providing a concave surface to support the convex side of the material, and a pair of spaced rolls to apply rolling pressure respectively to the two edges of the material from 20 opposite directions while the convex side thereof is supported. 30

14. Edge rolling apparatus for use with elongated material having a width greater than its thickness which has been previously bent transversely through a small angle comprising means providing a concave surface to support the convex side of the material, and a pair of spaced rolls to apply rolling pressure respectively to the two edges of the material from opposite directions while the convex side thereof is supported. 40

15. Edge rolling apparatus for use with elongated material having a width greater than its thickness which has been previously bent transversely through a small angle comprising a pair 45 of spaced rolls to apply rolling pressure respectively to the two edges of the material from opposite directions, and means on said rolls providing concave surfaces to support the convex side of the material. 50

16. Edge rolling apparatus for use with elongated material having a width greater than its thickness which has been previously bent transversely through a small angle comprising means to support the convex side of the material, and a pair of spaced rolls having conical surfaces to apply rolling pressure respectively to the two edges of the material from opposite directions, the conical angle being of sufficient size to result in the formation of beveled edges on the material. 60

17. Edge rolling apparatus for use with elongated material having a width greater than its thickness which has been previously bent transversely through a small angle comprising a pair of spaced conical rolls to apply rolling pressure respectively to the two edges of the material from opposite directions, and an annular flange surrounding each roll and separable therefrom, each flange having a concave surface for contact with the convex side of the material. 70

18. Edge rolling apparatus for use with elongated material having a width greater than its thickness which has been previously bent transversely through a small angle comprising a pair of spaced rolls to apply rolling pressure respec- 75

tively to the two edges of the material from opposite directions, and a stationary block having a concave surface arranged to contact with the convex surface of the material while the edges thereof are being rolled.

5 19. A roll for use in rolling metal comprising a member having a frusto-conical socket, a second member having a conical surface fitting in the

socket, and means to fasten the members together, the conical surface extending outside of the socket without change in shape to form one side of a circumferential grooved pass, the first mentioned member forming the other side of 5 said pass.

JOHN W. SHEPERDSON.
